SASH CONSTRUCTION

William S. Hamm and Harry D. Severson, Elkhart,
Ind., assignors to The Adlake Company, Chi-
cago, Ill., a corporation of Illinois

Application January 24, 1934, Serial No. 708,045

7 Claims. (Cl. 189—76)

This invention has to do with slidably mounted sash of the type commonly used in the windows of railway cars and buses, and is particularly concerned with the means employed for effecting a weather-tight association between the sash and the guides in which the latter is mounted.

The principal object of the invention is to provide an improved side rail structure which will give a smooth sliding fit with a guide and yet remain weather-tight under all the varying conditions to which a sash is subjected in service.

While the foregoing statements are indicative in a general way of the nature of the invention, other more specific objects and advantages will be apparent to those skilled in the art upon a full understanding of the novel structural features of the improved side rail fitting.

A preferred embodiment of the invention is presented herein for the purpose of exemplification, but it will of course be appreciated that the invention is susceptible of incorporation in other slightly modified structural forms coming equally within the scope of the appended claims.

In the accompanying drawing:

Fig. 1 is a fragmentary perspective view of one of the upper corners of a sash equipped with the improved side rail fitting of the invention, showing the sash slidably mounted in a guide;

Fig. 2 is a horizontal section through the side rail of the sash and the guide in which the fitting on the side rail is slidably mounted;

Fig. 3 is a horizontal section through the side rail and fitting, with the parts shown in separated relation; and

Fig. 4 is a fragmentary perspective view of a rail-less sash, showing the improved fitting applied directly to one of the side edges of a pane of glass.

As will be observed in the drawing, with reference particularly to Figs. 1 to 3 inclusive, each side rail 10 of the sash is made of sheet metal and is provided at the center of its outer edge with an outwardly projecting flange 11. The flange 11 carries a sealing member 12 which is adapted to project within and slidably coat with a grooved guide 13.

The sealing member 12 is composed of a strip of felt 14 or other similar material and a sheet metal channel 15. The felt is folded about and within the channel, as shown in dotted lines in Fig. 3, and the channel, with the felt applied thereto, is sprung frictionally onto the flange 11, the channel being preferably collapsed somewhat prior to application in order to grip the flange 11

tightly with the side walls of the channel converging a little toward the outer edge of the side rail.

After the sealing member 12 has been applied to the flange 11 of the side rail, frictional engagement of the parts will prevent any endwise movement of the member relative to the flange while allowing the member to be pulled off edgewise without much difficulty whenever it is desired to renew the felt. If a more secure association is desired, the sealing member 12 and the flange 11 may be transfixated at one or more points with a rivet or other readily removable fastening device, but this is not necessary, as the resilient clamping action of the walls of the channel, transmitted to the flange through the interposed felt, produces a connection which is sufficiently secure to withstand the stresses to which a slidably mounted sash is subjected in ordinary service.

The guide 13 is preferably, though not necessarily, of resiliently expandable construction, one of the side walls 16 thereof being yieldably held in position by a spring strip 17. When the felt covering 14 absorbs moisture and swells in the guide, the walls 16 of the guide will yield enough to compensate for the swelling, thereby maintaining a snugly weather-tight but readily slidable association between the side rail of the sash and the guide at all times.

The side rail fitting, hereinbefore referred to as the sealing member 12, is preferably so proportioned with respect to the depth of the groove in the guide 13 as to contact with the back 18 of the guide while the projecting edges 19 of the side walls of the guide are still in spaced relation to the opposed edge portions of the side rail 10, thereby preventing any metal-to-metal contact between the sash and guide parts, which insulation feature not only cushions the sash against vibration but is of especial advantage in connection with sash made of aluminum and other metals subject to electrolytic action.

In Fig. 4 a somewhat similar sealing member, composed of an inwardly sprung sheet metal channel 20 and a felt wrapping 21 is shown applied directly to one of the side edges of a pane of glass 22, thereby providing a felt covered side rail for an otherwise rail-less sash.

We claim:

1. In sash construction, a side rail provided with a rib, and a felt covered channel member fitted on the rib for sliding engagement with an associated guide.

2. In sash construction, the combination with a laterally expansible guide, of a sash having a

- 5   felt surfaced bearing portion for sliding coaction within the guide, the expansibility of the guide compensating automatically for either swelling or compacting of the felt, whereby to insure a smoothly sliding yet weather-tight engagement with the guide under either condition.
- 10   3. In sash construction, a sheet metal side rail provided at the center of its outer edge with an outwardly projecting flange, and a sealing member carried by the flange for sliding coaction with an associated guide; said sealing member consisting of a sheet metal channel and a strip of felt folded about and within the channel; and said channel with the felt thereon being sprung onto the flange in tight frictional engagement therewith.
- 15   4. In sash construction, a side rail provided at its outer edge with a relatively narrow outwardly projecting rib, and a sealing member fitted on the rib for sliding engagement with an associated guide, said sealing member consisting of a sheet metal channel and a strip of soft flexible material which is folded about and tucked into the channel, with the tucked-in portions of the same interposed between the side walls of the channel and the sides of the rib.
- 20   5. In sash construction, a side rail provided at its outer edge with a relatively narrow outwardly projecting rib, and a sealing member fitted on the rib for sliding engagement with an associ-

ated guide, said sealing member consisting of a sheet metal channel and a strip of soft flexible material which is folded about and tucked into the channel, with the tucked-in portions of the same interposed between the side walls of the channel and the sides of the rib, and with the back of the channel bowed and the side walls thereof converging toward the outer edge of the side rail.

5   6. In window construction, a sliding closure member, and metal channel members covered with felt or other suitable cushioning material sprung over opposite side edges of the closure member in tight frictional engagement with the latter for sliding engagement with associated guides.

10   7. In window construction, a sliding closure member, and metal channel members covered with felt or other suitable cushioning material sprung over opposite side edges of the closure member in tight frictional engagement with the latter for sliding engagement with associated guides, said covering material being in the form of strips which are folded about and tucked into the channel members, with the tucked-in portions interposed between the sides of the channel members and the side edges of the closure member.
